UNITED STATES PATENT OFFICE.

CHARLES LIBERMAN, OF NEW YORK, N. Y.

SHOE-RAISING-PLATFORM DEVICE.

Application filed August 19, 1926. Serial No. 130,259.

This invention relates to a shoe raising platform and has for an object to provide an improved simplified construction whereby a minimum number of parts are presented.

Another object of the invention is to provide a shoe raising platform wherein the parts will quickly and automatically move when released.

10 A still further object of the invention is to provide a shoe raising device in which a lazy tong structure is used, the construction being such that upon a proper release, means will function to cause the lazy tong structure to be extended and when properly actuated on by the foot will cause the lazy tong structure to be collapsed whereby the effective height of the person standing on the device will be varied.

20 In the accompanying drawings—

Figure 1 is a longitudinal vertical sectional view through a shoe raising platform disclosing an embodiment of the invention.

Figure 2 is a sectional view through Figure 1 on line 2—2.

Figure 3 is a horizontal sectional view through Figure 1 on line 3—3.

Referring to the accompanying drawings by numerals, 1 indicates a platform adapted to receive a shoe, said platform having a pair of webs 3 at the bottom. It is to be understood that two of these devices are used together as a rule and that a person will place a foot on each of the platforms 1 and then operate the mechanism herein described whereby the platforms may be raised or lowered so that the person may be moved upwardly or downwardly to work on a wall or ceiling or other place as desired. Co-

40 acting with the platform 1 is a base 4 which is provided with a pair of upstanding flanges 5, each of said flanges being provided with slots 6 and 7 through which the respective axles 8 and 9 extend. Each of the axles 8 and 9 carries a pair of rollers, namely, rollers 10 and 11. Suitable nuts 12 are provided at each end of each axle so as to hold the axles properly centered. The slots 6 and 7 permit a loose motion of the axles so that the rollers 10 and 11 may bear on the upper surface 13 of base 4. This causes the flanges 5 to act merely as guiding members for the axles as they move back and forth. A pair of arms 14 is connected with

50 axle 8 and a similar pair of arms 15 is connected with axle 9, said arms crossing at a central point where they are pivotally connected together by a rod or shaft 16, which rod or shaft also extends through the vertical guides 17. These guides are riveted or otherwise rigidly secured to the base 4 and cause the rods 16 to move at right angles to the surface 13 or usually in a vertical up-and-down direction. The arms 14 and 15 form part of the lazy tong structure 18. The upper arms 19 and 20 of the lazy tong structure 18 are mounted on the axles 21 and 22 which carry the respective pairs of rollers 23 and 24 adapted to bear against the surface 25 of the platform 1. Suitable nuts 26 are carried at each end of the axles 21 and 22 for preventing undue longitudinal movement. Comparatively strong springs 27 and 27' are connected to the axles 22 and 21 respectively, said springs at their 60 opposite ends being connected to posts 34 and 35 respectively. These springs are under tension so that they will continually act to move the axles 21 and 22 towards each other and thereby distend the lazy tong structure 18. This will cause the platform 1 to move away from the base 4. The springs 27 and 27' normally cannot function by reason of the notched locking bar 28, said bar having a series of notches 29 for each of the axles 8 and 9. This bar is resiliently held in a lower position by the various springs 32 at the center and at the ends, and bar 28 extends through slots 36 in their respective posts 37 and 38, which are rigidly secured to base 4. A cord or cable 33 is connected to each end of the locking bar 28 and is adapted to be grasped by the person standing on the platform 1. From Figure 1 it will be noted that the posts 37 and 38 are 70 provided with notches 39 adapted to accommodate the respective locking bolts or catches 40 and 41. These bolts or catches are urged by the respective springs 42 and 43 so that they will snap into any of the notches whenever permitted. A cable 44 is connected to each of the bolts 40 and 41 so that when it is desired to release the platform 1 cables 44 must be pulled and simultaneously therewith or shortly thereafter cables 33 must be pulled whereupon the platform 1 must be forced downwardly or may be allowed to move upwardly under the action of springs 27 and 27'. Use of the catches or bolts 40 and 41 is to make the 80

platform rigid. Without these catches there is a small give or yield to the lazy tong structure 18, but by using these catches the platform is rigidly held in any adjusted position.

When two devices are used, the weight is removed from one of the platforms 1 and cords or cables 44 and 33 are pulled until the catches or locking bolts 40 and 41 and locking bar 28 are all disengaged. This will permit springs 27 and 27' to function whereby the platform is raised as far as the foot 5 posed above the same will permit. The raising action at one time is usually not more than six inches. After the parts have been raised the desired distance, as for instance, six inches, the cords or cables 44 and 33 are released and locking bar 28 will resume the position shown in Figure 1 and also the bolts or catches 40 and 41 will move into certain of the notches 38. The weight of the workmen may then rest on the raised platform 1 and the other platform may then be raised in a similar manner. If the new 15 height is not sufficient, the operation will be duplicated once or as often as desired within the limits of the device.

When it is desired to lower the platform 1 the locking bar 28 is raised and the 20 catches 40 and 41 disengaged. After this has been done and while these parts are held in a disengaged position platform 1 is pushed downwardly by the weight of the person, said downward movement being any 25 desired distance, as for instance, six inches. The locking bar 28 is then allowed to resume its locking position as shown in Figure 1, and catches 40 and 41 allowed to snap into certain of the notches 39, and then the 30 other device is lowered in a similar manner. This action is continued until the lazy tong 35 18 has been completely collapsed or collapsed to the desired extent. If desired, straps or other fastening means can be associated with the platform 1 so as to connect the same with the foot of a workman, though ordinarily this is not necessary. Also, if desired, a board or plank can be placed across two of the platforms and the 40 platforms elevated as described so that the 45 device will act as a collapsible and distensible device for supporting a scaffolding.

What I claim is:

1. A shoe raising platform comprising a 50 lazy tong structure, a base associated with one end of the lazy tong structure, a platform associated with the other end of the lazy tong structure, a spring tending continually to distend said lazy tong structure, a vertically movable locking bar formed with means for locking the lazy tong structure against distension, and means extending from said bar to a position adjacent the platform whereby a person standing on a platform 55 may move the locking bar to an un-

locked position, and a spring for automatically returning said bar to a locking position when the bar is released.

2. A shoe raising platform device including a lazy tong, a platform carried by one end of the lazy tong, a spring continually tending to cause said lazy tong to be distended, a rod connected to each leg of the lazy tong at the lower end, a base formed with guiding means for guiding said rods in a back and forth horizontal movement at right angles to their axes, a vertically movable notched bar adapted to engage and lock said rods against movement, a spring for normally holding said notched bar in a locked position, and means extending from said notched bar to a point adjacent the platform whereby any one standing on the platform may raise the notched bar out of engagement with said rods and permit said spring to function.

3. In a shoe raising platform device a lazy tong structure, a platform adapted to be raised by the lazy tong structure, a base, a rod extending through each leg of the lower end of the lazy tong structure, means carried by the base for permitting said rods to move parallel to the base as the lazy tong structure is distended and collapsed, wheels carried by said rods resting on the base and movable along the base as the lazy tong structure is caused to function, a notched locking bar engaging said rods and normally locking the same against movement, and a spring for resiliently holding said notched bar in locking position.

4. In a shoe raising platform device a base formed with a pair of flanges, each flange having openings therein, a lazy tong having one end positioned near said base, a rod extending through each leg of the end of the lazy tong adjacent the base, said rods extending through said openings, said rods being movable parallel with the base, anti-friction rollers carried by each of the rods resting on the base, a notched locking bar mounted on said base, and spring means normally holding said locking bar so that said rods will be positioned in one of the notches thereof and thereby locked against movement.

5. In a shoe raising platform device a base provided with a pair of upstanding flanges, each flange having elongated openings, a lazy tong provided with a rod at the lower end of each leg, said rods extending through said openings, a locking bar carried by the base formed with a series of comparatively deep notches, said rods being adapted to fit into said notches and thereby be locked against movement whereby the lazy tong structure cannot be distended or collapsed, and a spring for normally holding said locking bar in a locked position.

6. In a shoe raising platform device a lazy tong structure, a base for supporting said

lazy tong structure, a platform supported by a lazy tong structure, a spring acting on the lazy tong structure to give the same tendency to distend, means for locking the lazy tong structure in different distended positions, a pair of posts connected with said base and extending through said platform, each of said posts having a series of notches, a catch

carried by said platform for each post, said catches being adapted to fit into any of said notches and flexible members extending from said catches to a point adjacent said platform whereby they may be disengaged whenever desired. 10

CHARLES LIBERMAN.
